UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

VALVE CHEST FOR ROCK DRILLS.

Application filed November 29, 1921. Serial No. 518,679.

To all whom it may concern:

Be it known that I, CHARLES C. HANSEN, a citizen of the United States, and a resident of Easton, county of Northampton, and 5 State of Pennsylvania, have invented a certain Valve Chest for Rock Drills, of which the following is a specification, accompanied by drawings.

This invention relates to fluid actuated 10 rock drills, more especially of the hammer type, but relates in particular to the valve chest construction for the motive fluid distributing valve.

A valve chest and spool valve of the type 15 to which this construction is applied, is disclosed in the copending application of Lewis C. Bayles, Serial #451,661, filed March 12, 1921, for spool valve for rock drills, which application is assigned to Ingersoll-Rand 20 Company. In such a valve chest, bushings in which the valve slides are adapted to be inserted into the valve chest from opposite ends, and the object of the present invention, is to provide a construction which insures 25 the proper assembling of the bushings in the valve chest and prevents the interchanging of the bushings. My valve chest construction is simple, cheap to manufacture and readily lends itself to production in 30 rock drills on a large scale.

Further objects of the invention will hereinafter appear, and the invention is illustrated in one of its preferred forms in the accompanying drawings, in which—

35 Figure 1 is a top plan view partly in horizontal section of so much of the back end portion of a rock drill as will serve to illustrate the invention.

Figure 2 is a side elevation of the same 40 portion of the drill, partly in longitudinal section,

Figure 3 is a detail perspective view in 45 longitudinal sectional elevation of the two bushings, adapted to be inserted in either end of the valve chest.

Figures 4 and 5 are detail diagrammatic 50 end views of the valve chest and bushings, taken from opposite ends partly in section, and illustrating the manner in which I prevent the wrong bushing from being inserted in a given end of the valve chest.

Referring to the drawings, a portion of the cylinder A of a rock drill of the hammer type is shown, having the hammer piston B

reciprocating therein and provided with the 55 reduced shank or extension C guided in the front cylinder washer D and adapted to impart blows of impact to the shank of the drill steel, not shown. Any suitable means may be provided for imparting rotation to 60 the drill steel, in this instance, a portion of the rotating device being indicated by the ratchet ring E located between the plate F and the back head G. The rifle bar H engages the piston B in the usual manner. 65 The water tube J with water tube inlet K and remainder of the back head construction, need not be further described, as it forms no part of the present invention.

The supply and distribution of motive 70 fluid for operating the tool is controlled by the usual throttle valve L having the handle O and the spool valve P mounted in the valve chest Q, adapted to be secured to the side of the cylinder A as by means of the 75 bolts R. In this instance, the valve is shown extending transversely across the valve chest, as a convenient construction. The parts of the drill cylinder are secured together by the usual through bolts S. The 80 throttle valve L in the valve chest controls the inlet T and motive fluid entering the inlet passes through the throttle valve to the supply passage U in the valve chest, which leads to the inlet ports V controlled 85 by the distributing valve P.

It is to be understood, that the cylinder A and valve chest Q are formed with suitable 90 ports and passages for distributing motive fluid to both ends of the cylinder, and for exhausting the fluid from the cylinder, as shown in detail in the aforesaid co-pending application, Serial No. 451,661 so that the 95 details of these ports and passages will not be further referred to herein. As in that application, the valve P is shown sliding on a bolt W, and within the bushings X and Y, which bushings are adapted to be inserted from opposite ends into the bore of the valve chest. The bushings X and Y are 100 formed with the radial ports X' and Y' respectively, through which motive fluid passes alternately to the forward and rearward ends of the piston.

These bushings, as shown, are separated 105 at the center, leaving a space Z communicating with the exhaust port a, and after the bushings and valve have been assembled in

the valve chest, the bolt W is inserted and tightened by means of the nut b, to hold the bushings in position.

In order to insure the proper assembling 5 of the bushings in the valve chest, portions of each of said bushings are made unsymmetrical, so that the bushing for one end of the valve chest will not fit the other end of the valve chest. A simple and convenient 10 way of constructing the valve bushings with unsymmetrical portions is to flatten the peripheries of the flanges c and d, at unequal distances from the centers or longitudinal axes of the bushings. By providing 15 portions on the valve chest with which the flattened portions of the bushing flanges are adapted to cooperate, I am enabled to insure the proper assembling of the bushings.

In the present instance, the flattened portion e of the flange c of the bushing X is nearer the axis of the bushing than the flattened portion f of the said flange. As shown in detail in Figure 3, the distance 2 is less than the distance 3. Likewise, the flattened 25 portion g of the flange d of the bushing Y, is at a lesser distance from the center or longitudinal axis of said bushing than the flattened portion h of the flange. In the detail drawings, in Figure 3, the distance 4 is less than the distance 5.

The bushing X is shown assembled in the proper end of the valve chest in Figures 1 and 2, in which case the flat portion e lies 35 opposite the wall j of the valve chest, and the flat portion f lies opposite the wall k of the cylinder, which might if desired be a portion of the valve chest. The bushing Y is also shown in the proper end of the valve chest in Figures 1 and 2.

40 By referring to Figures 4 and 5, it will be obvious that if an attempt is made to insert the bushing Y into the valve chest in the end in which the bushing X belongs, the flattened portion h of the flange d of the bushing Y, which is at the greater distance from the center, will overlap the wall j of the valve chest and prevent the bushing Y from being inserted into the end of the valve chest. Similarly, if the bushing X were 45 attempted to be inserted in the end of the valve chest in which the bushing Y belongs, the flattened portion f of the bushing X which is at the greater distance from the center, would interfere with the wall j' of the valve chest, and the bushing could not be inserted. I thus insure in a simple and efficient manner that a valve bushing is always inserted in the proper end of the valve chest, so that the proper ports in the 50 bushings correspond with the proper ports in the valve chest.

The outer faces of the bushings are also preferably grooved radially, as shown at o and p and copper gaskets or locking washers q are preferably inserted between the

head r of the bolt and the bushing Y and between the nut b and the bushing X. These locking washers may be formed with radial projections s, one of which is bent outwardly to engage the head or nut of the bolt, and another is bent into the groove o or p of a bushing, in order to lock the parts.

I claim:

1. In a fluid actuated rock drill, the combination of a cylinder and piston, a valve chest at the side of the cylinder, a distributing valve in said valve chest, removable valve chest bushings for the ends of the valve chest, each bushing having a flange formed with two flattened peripheral portions, the said flattened portions on each flange being at different distances from the center of the bushing, and a stop for each bushing formed by the walls at the ends of the valve chest, both stops being located on the same side of the longitudinal axis of the valve chest adjacent the openings for the bushings, the distance from the longitudinal axis of the bushing to one of the flattened peripheral portions being greater than the distance from that longitudinal axis to the stop and the distance from the said longitudinal axis to the other of said flattened peripheral portions being less than the distance from said axis to said stop, whereby 95 neither one of the bushings can be fitted into the valve chest opening provided for the other bushing.

2. In a fluid actuated rock drill, the combination of a cylinder and piston, a valve chest at the side of the cylinder, a distributing valve in said valve chest, removable valve chest bushings for the ends of the valve chest, each bushing having a flange formed with two flattened peripheral portions, the said flattened portions on each flange being at different distances from the center of the bushing, the flattened portions which are at the same distance from the center being on the same side of the longitudinal axis of each bushing, and a stop for each bushing formed by the walls at the ends of the valve chest, both stops being located on the same side of the longitudinal axis of the valve chest adjacent the openings for the bushings, the distance from the longitudinal axis of the bushing to one of the flattened peripheral portions being greater than the distance from that longitudinal axis to the stop and the distance from the said longitudinal axis to the other of said flattened peripheral portions being less than the distance from said axis to said stop, whereby 115 neither one of the bushings can be fitted into the valve chest opening provided for the other bushing.

In testimony whereof I have signed this specification.

CHARLES C. HANSEN.
